No. 818,466.

PATENTED APR. 24, 1906.

N. S. PRICE.
DEVICE FOR DRENCHING HORSES.
APPLICATION FILED AUG. 7, 1905.

UNITED STATES PATENT OFFICE.

NED S. PRICE, OF ERIE, PENNSYLVANIA.

DEVICE FOR DRENCHING HORSES.

No. 818,466.

Specification of Letters Patent.

Patented April 24, 1906.

Application filed August 7, 1905. Serial No. 273,148.

To all whom it may concern:

Be it known that I, NED S. PRICE, a citizen of the United States, residing at Erie, in the county of Erie and State of Pennsylvania, 5 have invented new and useful Improvements in Devices for Drenching Horses, of which the following is a specification.

This invention relates to devices for drenching horses and the like; and it consists in certain improvements in the construction thereof, as will be hereinafter fully described, and pointed out in the claims.

The invention is illustrated in the accompanying drawings, as follows:

15 Figure 1 shows a section on the line 1 1 of Fig. 2. Fig. 2 is a plan view, and Fig. 3 a side elevation.

A marks the receptacle into which the medicinal liquid may be placed. Secured to 20 the bottom of this receptacle is the nozzle B. This nozzle has the part b and the rearwardly-extending part b'. A passage b² extends through this nozzle. A passage a is arranged in the bottom of the receptacle leading 25 to the passage b² and is controlled by the valve C. A stem c extends upwardly from this valve through the top a' of the receptacle. The stem extends through a lug a², projecting from the side of the receptacle, and 30 the spring c' is arranged between this lug and the valve to keep the valve seated. A lever c², secured to the upper end of the stem, is pivoted on a lug a³, extending upwardly from the top a'. A chain c³ is suspended 35 on the end of the lever c², with a thumb-ring c⁴ at the end. The size of the receptacle is such and the length of the chain so arranged that when the receptacle is grasped by the operator the valve may be 40 opened by the action of the thumb on the ring c⁴. The top a' is funnel-shaped, and the opening through it is preferably closed by a valve or cover a⁴. This is secured to the top a' by a hinge a⁵. A handle a⁶ is provided for 45 opening this cover, and a spring a⁷ closes it. In filling the receptacle this cover is opened and the top acting as a funnel directs the material to the receptacle. With the cover closed the receptacle is entirely closed, so that 50 it may be handled without fear of wasting the liquid contained in it. When the device is in place and the valve opened, it is desirable to provide a vent, so that the liquid may run out quickly. This I accomplish by providing 55 the lugs c⁵ on the stems c in such position as

to engage the cover a⁴ as the stem c is lifted to raise the valve, so that as the valve is opened the opening through the top forming the vent is also opened.

I have provided the gage for indicating the amount of material in the receptacle. It 60 comprises the float D, from which the stem d extends. This stem passes through the opening a⁸ in the top and is provided with the 65 graduations d', by means of which the level of liquid in the receptacle may be ascertained.

With the nozzle formed as shown it may be introduced into the side of the mouth and then the part b' turned toward the rear, the lateral part b extending through the wall of 70 the mouth and the part b' extending rearwardly toward the throat of the animal. By having a valve connection between this and the receptacle the nozzle may be first put in place before the liquid is turned in. By 75 making the nozzle of this shape and providing the valve for preventing the flow of liquid until the nozzle is in such position the receptacle may be maintained in an upright position while being inserted. This permits of 80 the use of the gage, comprising the float and graduated stem.

Having thus described my invention, what I claim as new, and desire to secure by Letters Patent, is—

85

1. In a drenching device, the combination of a receptacle, a part b extending laterally from the receptacle, and a rearwardly - extending part b' said parts forming a nozzle unobstructed from the end of the part b' to 90 beyond the turn between the parts to permit of the nozzle being inserted in the side of the mouth with the jaws closed, and turned to bring the part b through the side of the mouth, and the part b' extending into or toward the throat, and a valve controlling the flow of liquid from the receptacle. 95

2. In a drenching device, the combination of a receptacle, a part b extending laterally from the receptacle, and a rearwardly - extending part b' said parts forming a nozzle unobstructed from the end of the part b' to 100 beyond the turn between the parts to permit of the nozzle being inserted in the side of the mouth with the jaws closed, and turned to bring the part b through the side of the mouth, and the part b' extending into or toward the throat, and a valve controlling the flow of liquid from the receptacle, a stem extending from said valve through the top of 105 110

the receptacle, and means within the reach of the operator's hand grasping the receptacle, for tripping the valve.

3. In a drenching device, the combination 5 of the receptacle A, the lateral part b, and the rearwardly-extending part b' forming the nozzle B unobstructed from the end of the part b' to beyond the turn between the parts, the valve C controlling the connection between 10 the receptacle and the nozzle, and the stem c extending from the valve through the top of the receptacle, a lever c² extending from the stem over the side of the receptacle, a lug a³ forming the fulcrum for the lever c², a chain 15 c³ secured to the lever, and the thumb-ring c⁴, secured to the chain.

4. In a drenching device, the combination of a receptacle for the liquid, said receptacle being provided with a vent, a nozzle extending 20 from said receptacle, a valve controlling the flow of liquid from the receptacle to the nozzle, means for closing the vent, and means for opening the vent and valve simultaneously.

25 5. In a drenching device, the combination with a receptacle, a nozzle extending therefrom, and a funnel-top arranged on said receptacle having an opening through which material may pass from the top into the receptacle, said opening also forming a vent for 30 the receptacle, means for closing said vent and means for opening said vent.

35 6. In a drenching device, the combination with a receptacle, a nozzle extending therefrom, and a funnel-top arranged on said receptacle, having an opening through which material may pass from the top into the receptacle, said opening also forming a vent for the receptacle, means for closing said vent, a 40 valve controlling the flow of liquid from the receptacle to the nozzle, and means for simultaneously opening the valve and the vent.

7. In a drenching device, the combination 45 of a receptacle for the liquid, a nozzle extending therefrom, a funnel-shaped top a' on the receptacle, having an opening therefrom for the passage of the material, a cover a⁴ for said opening, a hinge for securing said cover to the top, a spring a⁷ for holding said cover in closed position. 50

8. In a drenching device, the combination 55 of the receptacle A having the passage a through the bottom thereof, the lateral part b and rearwardly-extending part b' forming a nozzle B unobstructed from the end of the part b' to beyond the turn between the parts, the valve C controlling the opening, a stem c extending from the valve through the top, the funnel-shaped top a' having an opening 60 for the introduction of the material, said opening also forming a vent, a cover a⁴ for said opening, and means on the stem c for opening said cover.

9. In a drenching device, the combination 65 of a receptacle, a part b extending laterally from the receptacle, and a rearwardly-extending part b' said part forming a nozzle unobstructed from the end of the part b' to beyond the turn between the parts to permit 70 of the nozzle being inserted in the side of the mouth with jaws closed, and turned to bring the part b through the side of the mouth, and the part b' extending into or toward the throat, and a valve controlling the flow of liquid from the receptacle, the float D having 75 the graduated stems d extending upwardly therefrom through the top of the receptacle.

In testimony whereof I have hereunto set my hand in the presence of two subscribing witnesses.

NED S. PRICE.
